UNITED STATES PATENT OFFICE.

WILLIAM PETRY, OF CHICAGO, ILLINOIS, ASSIGNOR TO THE ACME CAR SEAL CO., OF CHICAGO, ILLINOIS, A CORPORATION OF ILLINOIS.

SEAL.

1,303,955.

Specification of Letters Patent. Patented May 20, 1919.

Application filed June 22, 1918. Serial No. 241,320.

To all whom it may concern:

Be it known that I, WILLIAM PETRY, a citizen of the United States of America, and a resident of Chicago, county of Cook, and 5 State of Illinois, have invented certain new and useful Improvements in Seals, of which the following is a specification.

The main objects of this invention are to provide an improved self-locking seal 10 for car doors and various kinds of closures where it is desired to prevent access or the removal of parts without detection; and to provide in a sheet-metal seal an improved arrangement and construction of the sealing 15 strap and casing adapted to prevent access thereto or injury to the locking mechanism either by manipulation of the strap ends or the insertion of a tool.

An illustrative embodiment of this invention is shown in the accompanying drawing, 20 in which—

Figure 1 is an enlarged fragmentary perspective view showing the structural arrangement of the ends of the sealing strap.

Fig. 2 is a perspective view of the stamping which forms the housing.

Fig. 3 is a perspective view of the completed housing with the ends of the strap locked therein.

Fig. 4 is a longitudinal sectional view of the same.

In the form shown, the seal comprises a sealing strap 1 having its ends formed for interlocking engagement with each other, 35 and a housing 2 for retaining and protecting the interlocking ends of the strap.

The strap 1 is formed of flexible resilient sheet metal and is of substantially uniform width except at its ends, where it is reduced 40 to form locking tongues. The end 3 is cut away at each side and then bent back upon itself to form a rearwardly inclined locking tongue 4 slightly narrower than the width of the strap, and the middle portion of the 45 folded end is cut away so as to provide a central lug 5 and a pair of prongs 6 adjacent to opposite edges of the strap. A hump 7 is pressed up near the middle of the tongue and is of hood shape so as to provide an 50 abrupt shoulder 8 at its rearward end and an inclined guide surface for guiding the coacting part on the end of the strap into engagement with the shoulder 8.

The other end 9 of the strap 1 is cut away

at the sides so as to provide a slightly narrower tongue with a shoulder 11 at each side. Near the front end of the tongue 10 there is a perforation 13, and immediately back of this, the metal of the tongue is cupped upward to form a hood-shaped 55 shield 12, the front edge of the opening 13 forming a shoulder 14 which coöperates with the shoulder 8 when the strap ends are interlocked. A short distance rearwardly of the shield 12 is a downwardly cupped 60 hood-shaped shield 15 open toward the front, and immediately above the shield 15 is a shield 16 which is formed by striking up a tongue 17, folding the same forward 65 against the body of the tongue 10, and cupping it upward.

The housing 2 is a sheet-metal stamping in the form of a pair of disks 17 and 18 connected by a contracted neck with an opening 20 located centrally in the neck. 75

The stamping is folded at the neck over the ends of the prongs 6 of the end 3 of the strap, and the lateral edges of the part 17 are folded up over those of the part 18, so that the tongues 6 are securely gripped between the adjacent flat portions of the parts 17 and 18. In order to give additional security to the connection between the strap 1 and the housing, said parts are all indented or otherwise crimped at 24. 80

The housing stamping 2 is cupped at 21 and 22 at each side of the opening 20 so as to provide space within the housing for the parts which are housed therein. The opening 20 forms the mouth into which the 90

initially free end 10 of the strap 1 is inserted. When said end 10 is inserted into the housing and pushed in as far as it will go, the end of said tongue 10 will ride over the hump 7 and be forced downward by the 95 inclined wall 22, at the back of the housing until the shoulder 14 snaps down into engagement with the shoulder 8 and allows the tongue 10 to straighten out as shown in Fig. 4. The shield 12 covers the hump 7, and the 100

superposed shields 15 and 16 receive and guard the lug 5 and fit the edges of the mouth 20 so as to completely fill the latter. There is therefore no room for the insertion of an implement of any kind into the mouth 105 20 without substantially distorting and mutilating the lips thereof, and even if it were possible to force an implement into

the mouth of the housing, the shields 15, 16, and 12 would prevent such implement from sliding along the upper surface of the lug 5 with a view to reaching and lifting the 5 shoulder 14 out of engagement with the shoulder 8. The ends of the prongs 6 abutting against the folded parts 25 at the sides of the mouth 20 and the crimping at 24 prevent any possibility of shifting the housing 10 backward along the strap end 3 so as to give access to the interlocking shoulders.

Likewise, the shoulders 11 prevent the 15 end 9 of the strap from being pushed into the housing so far as to buckle the tongue 10 with a view to releasing the shoulders 8 and 14. The shield 12, hump 7, and top of the housing all coöperate to prevent any possibility of the tongue 4 being buckled by a pull upon the end 9 of the strap 1.

20 The advantage of having the shoulder 8 formed on the tongue 4 instead of being formed directly upon the adjacent part of the strap 1, is that should there be any tendency of the end of the tongue 10 which carries the shoulder 14 to rise, the spring action of the tongue 4 would cause the shoulder 8 to rise with it and prevent the disengagement of said shoulders under any circumstances.

30 The term "hood-shaped" is intended to designate a form similar to that of the hump 7, having three or more of its sides connected with or bracing against the body upon which it is formed.

35 Although but one specific embodiment of this invention has been herein shown and described, it will be understood that numerous details of the construction shown may be altered or omitted without departing 40 from the spirit of this invention as defined by the following claims.

I claim:

1. A self-locking seal comprising a strap, 45 a forwardly projecting lug on one end of said strap, a shoulder on said strap rearwardly of said lug, a shoulder on the forward part of the other end of said strap adapted to have interlocking engagement with said first mentioned shoulder, a shield 50 struck out from said other end of said strap and adapted to receive said forwardly projecting lug when said shoulders are in interlocking engagement, and a housing surrounding said interlocking strap ends, said 55 shield and housing coacting to prevent access to said interlocking shoulders.

2. A self-locking seal comprising a strap, 60 one end of said strap being bent back upon itself to form a yielding tongue and a forwardly projecting lug, a shoulder on said tongue rearwardly of said lug, a shoulder on the forward part of the other end of said strap and adapted to have interlocking engagement with said first mentioned shoulder, a shield struck out from said other end

of said strap and adapted to receive and guard said forwardly projecting lug when said shoulders are in interlocking engagement and a housing surrounding said interlocking strap ends and shield. 70

3. A self-locking seal comprising a strap, a forwardly projecting lug on one end of said strap, a shoulder on said strap rearwardly of said lug, a shoulder on the forward part of the other end of said strap 75 adapted to have interlocking engagement with said first mentioned shoulder, a pair of superposed shields formed on said other end of said strap and adapted to receive and guard said forwardly projecting lug when 80 said shoulders are in interlocking engagement, and a housing surrounding said strap ends and coacting with said shields to prevent access to said shoulders.

4. A self-locking seal comprising a strap, 85 a housing formed of a strip of metal bent intermediate its ends to provide superimposed parts with an opening at each end thereof, one end of said strap extending into said housing through one of said openings 90 and being rigidly secured to said housing, said strap end being bent back upon itself to form a yielding tongue and a forwardly projecting lug; a shoulder struck up from said tongue rearwardly of said lug, a shoulder on the forward part of the other end of said strap, a shield struck out from said other end of said strap being adapted to be inserted in through the other opening of said housing 95 and have said shoulders and said lug and shield respectively enter into interlocking engagement so as to undetachably secure said strap ends in said housing, said housing being shaped adjacent to said other opening 100 so as to coat with said shield and prevent the insertion of a tool into said housing and obtaining access to said interlocking parts.

5. A seal of the class described, comprising a housing and a strap having one end 110 permanently fastened in the housing and having its lateral marginal edges clamped between the marginal portions of the housing; a locking shoulder formed on said strap end, said strap having its other end formed 115 to provide a shoulder adapted to interfit with said first-named shoulder when said strap ends are brought into endwise overlapping engagement within the housing, and a hollow shield carried by said other strap 120 end adapted to receive and protect the front end of said first strap end.

6. In a seal, a housing comprising a stamping folded upon itself and having an aperture in the folded part to form a mouth, 125 a strap having one end bent back upon itself and having its lateral edges permanently clamped between the opposed parts of the housing, a portion of the folded back part of said strap end being shaped to form a 130

tongue and sprung outward from the plane of the strap and having thereon a locking shoulder, the fold in said strap being embraced by the fold in the housing, and the 5 other end of said strap being adapted to enter said mouth and having thereon a shoulder coacting with the shoulder on said

tongue, and having thereon a hollow shield adapted to fill said mouth and to receive the adjacent end portion of said permanently 10 fastened strap end.

Signed at Chicago this 13th day of June 1918.

WILLIAM PETRY.
